SECURING DEVICE FOR WALLETS

Jack Barricini, Scarsdale, N. Y.

Application January 2, 1952, Serial No. 264,587

1 Claim. (Cl. 150—47)

1

The present invention relates to a securing device for wallets, and is particularly directed to a device for securing a billfold, wallet or pocketbook to the person of the owner.

It is the general practice for gentlemen to carry their billfolds, wallets or pocketbooks in the pockets of their trousers or in the inside pockets of their jackets. However, wherever the wallet is carried, there is the danger that it may be removed from its place of repose without the knowledge of the owner either inadvertently, as by falling out of the pocket in which it has been placed, or intentionally, as by a thief or pickpocket. Since important papers, such as, licences, identification and passports, as well as substantial sums of money, are commonly carried in wallets, such removal of the wallets from the person of the owner is often very costly, both in the financial loss involved and in the time lost in replacing the important and valuable papers that may be contained therein.

Accordingly, it is an object of the present invention to provide a device for attachment to a wallet or other pocketbook which is adapted to secure the wallet on the person of the owner.

Another object is to provide a device for attachment to a wallet which is constructed and arranged to secure the latter in pockets of different depths.

Still another object is to provide a device for attachment to a wallet which is easily operated by the owner to grip or release the article of wearing apparel in which the wallet is carried, and which, once it is in gripping engagement with the wearing apparel, strongly resists removal of the associated wallet from its place of repose.

A further object of the present invention is to provide a securing device for a wallet having the foregoing characteristics and constructed to afford an attractive appearance and to avoid tearing or other damage to the garment in which the associated wallet is carried.

The above and other objects, features and advantages of my invention will be apparent in the following description of a preferred embodiment thereof, given by way of example only, and to be read in connection with the accompanying drawing forming a part hereof.

Further, the invention consists in the combination, arrangement and details of construction of the several parts of the device, hereinafter described and then more clearly defined in the appended claim.

In the drawing:

Fig. 1 is an elevational view of a wallet having 55 the rear surface of the mounting plate 12 so that

2

a securing device attached thereto and constructed in accordance with an embodiment of the present invention, with the wallet received in a pocket and the securing device gripping the edge portion of the latter;

Fig. 2 is an elevational view of the wallet of Fig. 1, but showing the securing device positionally adjusted relative to the wallet for securing the latter in a deeper pocket;

Fig. 3 is a view of the wallet in open condition and looking at the inside thereof, with a portion of a compartment wall cut away to show a plate for attaching the securing device to the wallet;

Fig. 4 is a vertical sectional view of the wallet showing the securing device in side elevation;

Fig. 5 is a front elevational view of an element of the securing device embodying the present invention;

Fig. 6 is a side elevational view of the element of Fig. 5;

Fig. 7 is a rear elevational view of the element of Fig. 5;

Fig. 8 is a front elevational view of a plate provided for securing the element of Fig. 5 to the wallet;

Fig. 9 is a side elevational view of the plate of Fig. 8; and

Fig. 10 is a transverse sectional view taken along the line 10—10 of Fig. 3.

Referring to the drawing in detail, wherein the same parts are identified by the same reference numerals in the several views thereof, a securing device, embodying the present invention and indicated generally by the reference numeral 10, is there shown attached to a billfold, wallet or other similar pocketbook 11 of conventional construction.

The securing device 10 includes a mounting plate 12 (Figs. 5, 6 and 7), preferably of elongated, rectangular configuration, and having an elongated slot 13 formed therein. The side edges of the slot 13 are undercut as at 14 (Fig. 7) for a purpose hereinafter indicated. A flat slideable member 15 (Figs. 6 and 10) is mounted on the plate 12 for movement along the latter, and for this purpose is provided with a projection 16 (Fig. 10) extending from its rear face and into the slot 13. The rear end of the projection 16 is laterally enlarged, as at 17, within the undercut portion 14 of the slot to prevent separation of the slideable member 15 from the mounting plate 12. The undercutting of the slot 13 permits the lateral enlargement 17 to lie flush with the rear surface of the mounting plate 12 so that

movement of the slidable member will not be hindered when the plate 12 is secured to the outside of a wallet in the manner hereinafter provided.

A U-shaped guide member 18 (Figs. 5 and 6) is fixed to the slidable member 15 at points adjacent the ends of its parallel legs so that the guide member 18 extends substantially parallel to the slidable member and is spaced from the front face of the latter to provide a space 19 therebetween. As seen in Fig. 6, the free end of the guide member 18 is preferably flared or curved away from the member 15 to facilitate the entrance of the edge portion of a pocket into the space 19.

A gripping member 20, extending between the legs of the U-shaped guide member 18, is pivotally mounted adjacent one end on a pin 21 carried by the guide member. A torsion spring 22 (Fig. 6) is disposed between the slidable member 15 and the gripping member to continuously urge the free end of the latter in the direction toward the front face of the slidable member 15. Prongs or teeth 23 extend rearwardly from the free end portion of the gripping member to securely grip fabric or other material disposed in the space 19. A head 24 is formed integral with the gripping member 20 and extends in the opposite direction from the pivot pin 21 so that, when the head 24 is pressed manually toward the slidable member 15, the prongs 23 are withdrawn from the space 19 to permit the edge portion of a pocket to be inserted in, or removed from, that space.

As seen in Figs. 1 and 2, the mounting plate 12 is attached to the wallet 11 at the outside thereof and adjacent and at right angles to the top end edge of the wallet. In order to provide for such attachment of the mounting plate to the wallet, an attachment plate 25 (Figs. 3, 8 and 9) is disposed against the inside of the wallet wall and suitable fastening members, for example, screws 26 extending through holes 27 in the plate 25, through the wallet wall and into tapped holes 28 in the mounting plate 12, are employed to fasten together the plates 12 and 25 with the wallet wall therebetween. Using the particular fastening members detailed above, the front face of the plate 12 remains smooth, and there are no projections to interfere with the movement of the slidable member 15 along the slot 13.

In using the securing device 10 for holding a billfold, wallet or pocketbook in a pocket or other similar place of repose, the slidable member 15 is first adjusted along the slot 13 so that the edge portion 29 (Figs. 1 and 4) of the pocket will reach into the space 19 between the guide member 18 and the member 15, when the wallet is resting against the bottom of the pocket. The wallet is then inserted into the pocket, while depressing the head 24 on the gripping member 20, so that the edge portion 29 of the pocket may enter the space 19. When the head 24 is released, the

spring 22 urges the gripping member 20 towards the member 15 so that the prongs 23 grip the material of the edge portion 29 to prevent removal of said edge portion from space 19, and consequently to prevent removal of the wallet 11 from its place of repose within the pocket.

The wallet can be removed from the pocket without tearing the material of the edge portion 29, only after the head 24 of the gripping member is again depressed. It is apparent that the securing device 10, constructed and arranged as described above, will prevent the accidental removal of the associated wallet from the pocket, and will greatly discourage the removal of the 15 wallet by pickpockets or thieves. Further, it is apparent that the device is adjustable to secure the associated wallet in pockets of different depths.

While I have illustrated a preferred embodiment of my invention by way of example, it is apparent that changes and modifications, obvious to one skilled in the art, may be made therein without departing from the spirit and scope of the invention as defined in the appended claim.

25 What I claim is:

A device for securing a wallet and the like in a pocket; said device comprising a mounting plate adapted to be secured to the outside of a wallet, a slidable member, means mounting said slidable member on said mounting plate for positional adjustment relative to the latter, a U-shaped guide member fixed at the ends of its parallel side legs on said slidable member and spaced from the latter to define a downwardly opening space therebetween for receiving the edge portion of a pocket in which the associated wallet is disposed, a gripping finger pivotally mounted at one end between said ends of the parallel side legs of the guide member and extending between said side legs, spring means acting on said finger and urging the latter to pivot in the direction moving the free end of said finger laterally into said space for holding the edge portion of a pocket in said space to thereby prevent removal of the associated wallet from the pocket, and an actuating head extending from the pivoted end of said finger so that manual pressure on said head will effect removal of said free end of the finger from said space.
